UNITED STATES PATENT OFFICE.

MAX F. EISNER, OF NEW YORK, N. Y.

GARMENT-FASTENER.

SPECIFICATION forming part of Letters Patent No. 746,478, dated December 8, 1903.

Application filed February 9, 1903. Serial No. 142,475. (No model.)

To all whom it may concern:

Be it known that I, MAX F. EISNER, a citizen of the United States, and a resident of the city of New York, borough of Brooklyn, in the 5 county of Kings and State of New York, have invented a new and Improved Garment-Fastener, of which the following is a full, clear, and exact description.

This invention relates to improvements in 10 garment-fasteners, particularly fasteners for the fronts of corsets, and the object is to provide a fastener by means of which the fronts of a garment may be quickly drawn together and secured with very little exertion on the 15 part of the wearer.

I will describe a garment-fastener embodying my invention and then point out the novel features in the appended claims.

Reference is to be had to the accompanying 20 drawings, forming a part of this specification, in which similar characters of reference indicate corresponding parts in all the views.

Figure 1 is a perspective view of a garment-fastener embodying my invention and showing 25 the parts as closed and locked. Fig. 2 is a front view showing the busk members as separated. Fig. 3 is a section on the line 3 3 of Fig. 2. Fig. 4 is a section on the line 4 4 of Fig. 2. Fig. 5 shows an end portion of the 30 busk, and Fig. 6 is a perspective view of a tool that may be employed for drawing the parts to closed position.

Referring to the drawings, 5 6 designate 35 the two busks designed to be secured to the meeting or front edges of a corset or other garment. For the purpose of securing the busks to a garment the busks may be provided with perforations through which rivets or threads may pass into the garment. These busks are 40 sufficiently resilient to conform to the body of the wearer. Each busk has its opposite edges turned over the body portion, as indicated at 7 8, there being a space between the two opposite edges which forms a guideway for the 45 pivot-lugs of the fastening-links, as will be hereinafter described. One edge wall of each busk is provided with hook members 9, the points of which are extended in the direction of movement of the fastening-links to closed 50 position.

The locking device proper consists of a series of links 10 11, the two links of a pair being pivot-

ally connected together and the adjacent ends of pairs of links being also pivotally connected together, as clearly indicated in the drawings. The pivotal connections between pairs of links consists of headed lugs 12, the shank portions of the lugs being made to slide freely in the slideway between the opposite edges of the busks. The headed portions, however, 55 are considerably wider than said slideway. Each busk near one end is provided with an enlarged opening 13, through which the heads of the lugs 12 may pass when attaching the links to the busk. The busk is also provided 60 with an opening 14 to receive a fastening-lug or button 15, which is slotted, so that it may yield inward and outward—that is, the lug 15 may be forced through the opening 14 by the head contracting and when through the head 65 will expand, so that the same will engage against the side portions of the busk, as clearly indicated in Fig. 5.

It will be noted that the shank portion of 70 the button 15 is somewhat greater in diameter 75 than the width of the slot or guideway between the opposite edges of the stay. Therefore the lower ends of the lower links are practically anchored and will be prevented 80 from movement longitudinally of the stays, but will be permitted to swing as the other links are drawn along the stays or busks. The two links 16 and 17 at the opposite end are free one from the other—that is, they are 85 not pivotally connected at the center, as are the links first described. This is to permit the movement of the said links 16 and 17, so that the shanks 18 of the fastening-lugs may be moved out and into engagement with the 90 hook members 9 of the busks, whereby the 95 said busks may be adjusted and held in any desired position. The shanks are each provided with a head 19, which will prevent their movement outward from the stays. It will be noted that the head 19 is eccentric to the shank 18, or, in other words, it is cut away at the side of the hook members 9. By this arrangement it is obvious that the shanks 18 may pass freely into engagement with the 100 hooks.

It is to be understood that the busks may be secured to the meeting edges of a garment in any suitable manner.

In the operation after passing the several

buttons or lugs 12 through the openings 13 and the buttons or lugs 15 through the openings or socket members 14 the links are to be drawn lengthwise of the stays, and when the 5 garment is sufficiently tight the shanks 18 are to be engaged with the hooks. Any suitable means may be employed for drawing the 10 links. I have here shown an instrument consisting of a handle 20, having swinging hook members 21, designed to be engaged in perforations 22 at the ends of the links 16 and 17.

It is to be understood that the fastening-hooks may be arranged at either end of the 15 busks without departing from the spirit of my invention—that is, the busks may be fastened to the garment with the hook members pointing upward or they may be secured to the garment with said hook members pointing 20 downward.

Having thus described my invention, I 25 claim as new and desire to secure by Letters Patent—

1. A garment-fastener, comprising busks having their edges turned over and inward, 25 one edge of each busk having hook members, a series of pairs of pivotally-connected links, the pivotal connections between adjacent 30 ends of the pairs of links being headed and designed to pass in the space between the turned-over edges, means for removably engaging the ends of a pair of links at one end with the busks, and lugs or buttons on the 35 ends of the links at the opposite end for engaging the said hook members, substantially as specified.

2. A garment-fastener, comprising a pair of busks, each busk having its opposite edges turned over and inward, one edge being provided with hook members, a series of pairs of links pivotally connected together, the pivots having headed portions, the shanks of said pivots being adapted to pass freely through the space between the turned-over edges, each busk having an enlarged opening near one end through which the heads of the pivots 40 may pass, each busk also having an enlarged opening near the first-named enlarged opening, compressible lugs on the ends of the first links of the series for engaging in said last-named enlarged openings, and headed lugs 45 on the ends of the links at the opposite end of the series, the shanks of which are designed to engage with the hook members of the stays, and the heads being eccentric to the shanks, the said last-named end links being free, the 50 one from the other, substantially as specified.

3. A garment-fastener, comprising a pair of busks, hook members on the busks, a series of pivotally-connected links operating to move in one direction to draw the busks together 60 and lugs on the end links for engaging the said hooks, substantially as specified.

In witness whereof I have signed my name to this specification in the presence of two subscribing witnesses.

MAX F. EISNER.
